ELEVATOR COMPANY, A CORPORATION OF NEW JERSEY.

HYDRAULIC TRANSMISSION MECHANISM.

1,288,274.

Specification of Letters Patent. Patented Dec. 17, 1918.

Application filed March 12, 1914. Serial No. 824,086.

To all whom it may concern:

Be it known that I, AUGUST SUNDH, a citizen of the United States, residing in Hastings-upon-Hudson, in the county of 5 Westchester and State of New York, have invented a new and useful Improvement in Hydraulic Transmission Mechanism, of which the following is a specification.

My invention relates to a system of control for hydraulic transmission mechanism, and is particularly adapted to control mechanism comprising a pump operated by a prime mover such as an electric motor, said pump supplying fluid to a second motor 15 which may be operatively connected to any mechanism that it is desired to operate.

One of the objects of the invention is to start and stop the electric motor and fluid motor simultaneously, and to provide an 20 electrical control system for automatically varying the torque and speed of the two motors simultaneously, throughout the periods of starting, stopping and acceleration.

Still another object of the invention is 25 to provide an automatic system of electrical control for power transmission mechanism of the class above described, whereby the operation of the prime mover and transmission mechanism can be maintained at any 30 desired speed throughout the entire range thereof.

Essentially the invention consists in the combination of a driving member comprising an electric motor, with hydraulic transmission mechanism of the character herein disclosed. The characteristic of the electric motor is well known regarding the current consumption of the same under load at starting, it being a well known fact that 35 the starting current greatly exceeds the normal running current, and furthermore the characteristic of the hydraulic transmission mechanism of the character herein disclosed, is also well known, in that the torque 40 of the fluid motor varies inversely as the speed, or in other words, as the amount of fluid delivered thereto by the pump. The object now is to start the electric motor and hydraulic transmission mechanism simultaneously, which by my invention is effected 45 by means of a manually operable controller, and further to provide means for automatically accelerating the electric and fluid motors simultaneously; thus the current 50 consumption of the motor will be a minimum and practically constant throughout

the periods of starting and acceleration to full speed and vice versa, and throughout the entire ranges of speed of the electric motor, the speed and torque of the fluid 60 motor will be automatically varied simultaneously therewith.

The accompanying drawing shows electrically operated hydraulic transmission mechanism, an automatic system of electrical control therefor and a manually operable control arranged in accordance with my invention.

The herein following description relating to the hydraulic transmission mechanism, will be brief, since the said mechanism is fully shown and described in detail, in my co-pending application, Serial Number 764,994, filed May 2, 1913.

The fluid pressure motor F comprises a 75 plurality of double acting cylinders whose pistons 1, are connected to a common crank pin 2. A driven member comprises a cable sheave 3 which is keyed to the crank shaft and is adapted to receive the hoisting 80 cables of an elevator or other hoist, although if desired the sheave 3 may be replaced by a belt pulley, gear, or other device whereby power may be transmitted from the crank shaft to any desired power consuming device. 85

The pump is adapted to deliver fluid under pressure to the fluid motor F. The stroke of the pump plungers 5, is controlled by means of a tilting head 6, carried upon 90 a shaft 7 in anti-friction bearings 8. The right hand end of the tilting head is provided on its inner circumference with a ball race 4 which is secured in place by means of a ring 9 and coacting ball race 9' 95 carried by a ring 13, which is concentric with the shaft 7, but is adapted to be shifted to an eccentric position with respect to the shaft 7 by means of a sliding wedge 10. The latter is arranged to slide longitudinally in a slot in the shaft by means of a lever 11, which is bifurcated in its lower end and has a pair of oppositely disposed pins which enter a circumferential groove in the part 12, which is integral with the key or wedge 10. By this arrangement the eccentricity of the ring 13 can be varied from zero to a maximum in either direction, by sliding the wedge lengthwise of the shaft by means of the lever 11. The 100 length of the stroke of the plungers will 105 obviously depend upon the amount of tilt 110

or inclination given to the tilting head by means of the wedge, and since this factor may be varied at will, the output of the pump may be controlled within predetermined limits, or if desired, the pump may be arranged to reverse the direction of flow of fluid by moving the wedge in a right hand direction past center.

A rotary valve 14 is operated from the pump shaft and is adapted to have a sliding movement thereon. This valve directs the fluid between the pump and fluid motor. Means for imparting a sliding movement of the valve 14 upon the shaft 7 comprises a grooved collar 15, provided on either lateral face with ball thrust bearings which are secured to or carried upon the valve. A pivoted lever 16 has a pin on it which rides in the groove on said collar, the arrangement being such that the valve may be shifted longitudinally of the shaft by means of the lever 16. The latter is provided with a pin 17 at its other end, which pin is adapted to ride in a cam slot 18 formed in the cam 19. The lever 11 by which the wedge 10 is shifted is also provided with a pin 20 which rides in a cam slot 21 in the cam 22. Both of the cams 19 and 22 are secured to a shaft 23, carrying a pinion 24. Thus it will be seen that by rotation of the pinion, the stroke of the pump plungers and shifting of the valve is effected simultaneously.

The pinion 24 is rotated by means of a fluid actuated piston 25, having a rack 26 formed integrally or otherwise connected with the piston rod 27. A pilot valve 28 directs the fluid from a supply pipe 29 into chambers 30 or 31, above and below the piston 25. Stems 32 and 33 of the pilot valve 40 and pistons respectively, are connected in the usual manner by a lever 34, which is connected through another lever 35 to an arm 36 pivoted at 37. A plurality of electromagnets A, A', A², A³, A⁴, are operatively connected to the arm 36, at the right of the pivot point and are adapted to operate successively in the order named to effect a graduated movement of the pilot valve 28 in a downward direction; and likewise a plurality of electromagnets B, B', B², B³, B⁴, are operatively connected to the rocker arm 36, at the left of the pivot point and are adapted to operate successively in the order named to effect a graduated movement of the pilot valve 28 in an upward direction.

It will now be seen from the above description that the inclination given to the tilting head by means of the wedge 10 is controlled within pre-determined limits by the electromagnets A, A', etc., and B, B', etc. The electromagnets A, A', etc., control the movement of the wedge in a right hand direction past center, and the electromagnets B, B', etc., control the movement of the wedge in a left hand direction past center.

These magnets of course likewise control the movement of the valve 14 also.

A prime mover such as an electric motor M, is adapted to drive the pump shaft 7, said motor being preferably a shunt wound motor. A sectional resistance 38 in the motor circuit is controlled by a plurality of electromagnetic switches C, C', C², C³, and C⁴. As herein shown I provide five switches for controlling the said resistance, but any desired number may be used, according to the amount of resistance used and the desired refinement of operation. These switches are provided with windings 39, 40, 41, 42 and 43, one of the terminals of each winding running to a manually operable switch D, the other terminals of said windings being connected to a common conductor 44, which is connected at a suitable point in the resistance. The manually operable switch D comprises a lever 44, which actuates a contact segment 45, said segment being adapted to engage the contacts 46 when the lever is moved to the left, and contacts 47 when moved to the right.

The cores 48, of the windings 39, 40, 41, etc., are adjusted in a well known manner as by means of suitable adjusting members 49 to effect the successive operation of the switches C, C', etc., in the order named, when the circuits for the windings 39, 40, 41, etc., are closed simultaneously, or in other words when the lever 44 is moved to its full left or right hand position. The closing of each switch C, C', etc., effects the cutting out of a portion of the resistance 38, thereby effecting a corresponding increase in the speed of the motor, until the last section is cut out, whereupon the motor will run at full speed.

Switches J, J', J², J³, and J⁴, are also controlled by the cores of the windings 39, 40, etc. These switches control the circuits for the electro-magnets A, A', etc., and B, B', etc., dependent on the direction of movement of the hand lever 44, so that the successive operation of said electro-magnet is effected simultaneously with the successive operation of the switches C, C', etc., which control the resistance 38.

One of the terminals of each of the windings of the electromagnets A, A', etc., are connected to contacts 50, 51, 52, 53 and 54, associated with the switches J, J', etc., the other terminals thereof being connected to a common conductor 55 connected to one of the contacts 46. One of the terminals of each of the windings B, B', etc., are connected in parallel with the terminals of the windings A, A', etc., which are controlled by the switches J, J', etc., the other terminals thereof being connected to a common conductor 56, which is connected to one of the set of contacts 47.

It is to be here pointed out that the elec-

tric motor is adapted to run in one direction only, since a reversal of the driven member 4 is effected by reversing the direction of flow of fluid between the pump and fluid motor, this operation being controlled from the switch D.

An electromagnetic main line switch H, is controlled from the switch D. G is a knife switch, connecting the source of current supply designated + and -, with the electromagnetic switch.

The operation will now be described; the parts as shown are in normal position at rest. By moving the lever 44 to the right, 15 so that the segment 45 spans the first three contacts of the set 47, a circuit is established for the winding of the main line switch as follows: from the + conductor, through conductor 57 to conductor 58, which 20 is a common conductor connecting with the first contact of each of the sets 47 and 46, through the first contact to segment 45, to the third contact, conductor 59, through the winding of the switch H, conductor 60, to - line. The switch H will now close, thereby 25 closing a circuit for the motor, which circuit includes all of the resistance 38. The motor will now start up at slow speed. Further movement of the segment into engagement with the fourth contact closes a circuit for the winding 39, as follows: from conductor 58 to first contact, contact segment 45, through the fourth contact to conductor 61 which is also connected to the 30 fourth contact of the set 46, conductor 62, through the winding 39, to the conductor 44 connected to the resistance 38. The winding 39 now receiving current effects the closing of the switches C and J. The switch 35 C now being closed, cuts out the first section of the resistance 38, and effects an increase in the speed of the motor M, but it is to be noted that the switch J closes a circuit for the winding of the electromagnet B, 40 the circuit therefore being as follows: from conductor 58, through the first contact to segment 45, to second contact, conductor 56, through the winding of the electromagnet B, conductor 63, through switch J, conductors 45 64 and 65 to - main. The electromagnet B now receiving current, will rock the arm 36 a small amount in a counter-clockwise direction and effect a small amount of movement of the pilot valve in an upward direction 50 thereby connecting the chamber 30 with the source of supply. A small amount of fluid will now flow into the chamber 30 and effect a downward movement of the piston 25 a predetermined amount, which effects the rotation of the cams 22 and 19 a predetermined amount in a counter-clockwise direction, thereby moving the wedge 10 a predetermined amount to the left of center to tilt the head from a concentric to an eccentric 55 position, whereupon the same will now op-

erate and effect the reciprocation of all the pump plungers in their respective cylinders. The pump will now deliver but a small quantity of fluid to the fluid motor at a great pressure, and it is to be particularly noted here, that since the stroke of the pump piston is comparatively slow, only a light load is placed upon the electric motor and the same will therefore not draw an excessive amount of current to operate the pump, but 75 a powerful torque will be delivered by the fluid motor, since as before stated herein, the torque of the fluid motor varies inversely as the speed, or in other words, as the amount of fluid delivered thereto by the 80 pump. Now upon the continued movement of the lever 44 to engage the remaining contacts, the remaining switches C', C'', etc., and J', J'', etc., will close successively in the order named, thereby cutting out the remaining steps of resistance, thus causing a gradual acceleration of the electric motor to full speed, and simultaneously as each of the remaining steps of resistance are cut out, a predetermined increase in the stroke of the 85 pump plungers is effected, thereby increasing the quantities of fluid delivered by the pump to the fluid motor, but at proportionately decreasing pressures. Thus the fluid motor will accelerate to full speed, depend- 95 ing of course on the load thereon.

Thus it will be seen that the electric motor and fluid motor are started practically simultaneously, and the automatic variation in the speed and torque of the two motors 100 throughout the entire range from zero to maximum is effected simultaneously. It will thus be seen that a powerful torque is delivered by the fluid motor in starting which torque decreases as the speed increases, and furthermore a minimum amount of current 105 is consumed by the electric motor, which current will be practically constant throughout the entire range of speed of the motor.

It is to be further noted that the rate of 110 speed of the electric motor may exceed that of the fluid motor, said speed of the fluid motor being automatically controlled and in proportion to the speed of the electric motor, throughout the period of acceleration. 115

When the windings B, B', etc., are de-energized upon stopping, only moving the lever 44 to its central position as shown, the weighted arms 65 and 66 which are pivoted at 67 and 68, respectively, serve to return 120 the arm 36 and the parts connected therewith to their normal positions.

It will be here noted that the operation of the electric motor and fluid motor can be maintained at any predetermined intermediate speed between the minimum and maximum, by means of the lever 44, and furthermore, if said lever is moved either to its full right or left hand position, the electromagnetic switches will operate successively 130

in a well known manner to cut out the sectional resistance 38, since the common conductor 44 of the windings 39, 40, etc., is connected at a point on said resistance, and the other ends thereof being connected through the switch D to the + main and thus the energization of said windings depends on the counter-electromotive force of the rotating armature.

10 The operation of the driven member 4 in a reverse direction is effected by moving the lever 44 to the left to engage the contacts 46. In this operation the direction of rotation of the electric motor is unchanged, 15 but the electromagnets A, A', etc., will now operate the pilot valve 28 in a downward direction, thereby effecting a movement of the wedge 10 in a right hand direction past center and resulting in reversal of fluid between the pump and fluid motor. The mode 20 of operation, etc., of the various parts by moving the lever 44 to the left is similar to that just described by moving the lever to the right, and therefore does not necessitate 25 further explanation.

It is to be distinctly understood that my invention is broadly applicable to the various types of variable speed transmission mechanism having a torque and speed characteristic which vary in inverse ratio, and said mechanism being adapted to be driven by a prime mover, and it is to be further understood that although I show herein a hydraulic transmission system, I wish not 35 to be limited in the application of my invention to the particular power transmission system herein disclosed.

What I claim as new and desire to secure by Letters Patent of the United States is:—

40 1. A driving and driven member, power transmission mechanism interposed between said members, means for starting and automatically accelerating the driving member from zero to maximum under variable loads, 45 and means for starting and automatically accelerating the power transmission mechanism simultaneously with the driving member.

2. A driving and driven member, power 50 transmission mechanism interposed between said members, manually operable means, and means controlled thereby for starting and automatically accelerating the driving member and power transmission mechanism 55 simultaneously.

3. The combination with fluid power 60 transmission mechanism, a prime mover for driving the same, means for starting and accelerating the prime mover, and means controlled by the first named means for effecting the operation of the hydraulic transmission mechanism simultaneously with the prime mover.

4. The combination with fluid power 65 transmission mechanism, an electric motor

for driving the mechanism, and means for controlling said electric motor and fluid power mechanism to effect the starting, stopping, and acceleration thereof simultaneously throughout their entire range of 70 speeds.

5. The combination with fluid power transmission mechanism, an electric motor for driving the same, means for starting and automatically accelerating the electric motor 75 from zero to maximum under variable loads, and means for starting and automatically accelerating the fluid power transmission mechanism simultaneously with the electric motor.

6. The combination with fluid power transmission mechanism, an electric motor for driving the same, a manually operable member, and means controlled thereby for starting and automatically accelerating the 85 electric motor, and fluid power transmission mechanism simultaneously.

7. The combination with fluid power transmission mechanism, a non-reversing electric motor, means for starting and automatically accelerating the electric motor 90 from zero to maximum under variable loads, and means for starting the fluid power transmission mechanism in either direction and automatically accelerating the same simultaneously with the electric motor.

8. The combination with fluid power transmission mechanism, an electric motor for driving the same, means for connecting the motor with a source of power supply, 100 electro-responsive means for accelerating said motor in proportion to the load thereon, and means dependent on the acceleration of the electric motor for controlling the acceleration of the fluid power transmission 105 mechanism.

9. The combination with fluid power transmission mechanism, an electric motor for driving the same, means for connecting the motor with a source of current supply, 110 electromagnetic means for automatically varying the speed of the electric motor, and electrically controlled means for automatically varying the speed and torque of the fluid power transmission mechanism simultaneously with the variation of the electric 115 motor speed.

10. The combination with fluid power transmission mechanism, an electric motor for driving the same, a manually operable 120 controller for connecting said motor with a source of power supply, electro-responsive mechanism for automatically varying the speed of the electric motor, and means controlled by said electro-responsive means for 125 starting and automatically varying the speed of the fluid power transmission mechanism simultaneously with the electric motor.

11. The combination with a fluid pressure motor, pumping mechanism adapted to sup- 130

ply said motor with fluid under pressure, an electric motor for driving the pumping mechanism, means dependent on the load on the motor for starting and effecting a variation in the speed of the electric motor, and means for starting and effecting a variation in the speed of the fluid pressure motor simultaneously with the electric motor.

12. The combination with a fluid pressure motor, pumping mechanism adapted to supply said motor with fluid under pressure, an electric motor for driving the pumping mechanism, means for connecting the electric motor with a source of current supply, electro-responsive means for effecting a variation in speed of the electric motor, and electrically controlled mechanism dependent on the variation in the speed of the electric motor, for automatically varying the speed and torque of the fluid pressure motor, by varying the quantity of fluid delivered by the pumping mechanism.

13. The combination with a fluid pressure motor, pumping mechanism for supplying said motor with fluid under pressure, an electric motor driving the pumping mechanism, means for starting and automatically effecting a variation in the speed of the electric motor from zero to maximum under variable loads, and means for starting and automatically varying the speed and torque of the fluid motor in inverse ratio, simultaneously with the electric motor, by varying the output of the pumping mechanism.

35 14. The combination with a fluid pressure motor, pumping mechanism for supplying said motor with fluid under pressure, an electric motor for driving the pumping mechanism, means for starting and automatically effecting a variation in the speed of the electric motor, and means for starting and automatically varying the speed and torque of the fluid motor in inverse ratio, simultaneously with the variation in speed of the electric motor.

15. The combination with a fluid pressure motor, pumping mechanism for supplying said motor with fluid under pressure, an electric motor for driving the pumping mechanism, means for connecting the electric motor with a source of current supply, electro-responsive means for varying the speed of the electric motor in time proportion to the load thereon, and means dependent on the variation in speed of the electric motor for effecting a variation in the speed and torque of the fluid motor in inverse ratio, by varying the quantity of fluid delivered to the fluid motor.

16. The combination with a fluid pressure motor, pumping mechanism for supplying said motor with fluid under pressure, an electric motor, a manually operable controller operable to connect the electric motor with a source of current supply, electro-responsive means controlled by said manual controller for automatically varying the speed of the electric motor, and means controlled by said manual controller, but dependent on the variation in speed of the electric motor, for automatically varying the speed and torque of the fluid motor in inverse ratio.

17. The combination with a fluid pressure motor, a pump for supplying said motor with fluid under pressure, an electric motor, means for starting and automatically accelerating the electric motor from zero to maximum in time proportion to the load on the fluid motor, and means for starting and automatically accelerating the fluid motor simultaneously with the electric motor, by varying the fluid output of the pump, whereby the speed and torque of the fluid motor will vary in inverse ratio.

18. The combination with a fluid pressure motor, a pump for supplying fluid under pressure thereto, an electric motor for driving the pump, a manually operable controller, an electro-magnetic switch controlled thereby for connecting the electric motor with a source of current supply, electro-responsive means controlled by said controller for automatically accelerating the electric motor from zero to maximum and in time proportion to the load on the fluid motor, and electrically operated mechanism controlled by said electro-responsive means for automatically varying the output of the pumping mechanism simultaneously with the variation in speed of the electric motor.

19. The combination with a fluid pressure motor, a pump for supplying fluid under pressure thereto, an electric motor operatively connected to the pump, means for starting and automatically accelerating the electric motor, means for varying the output of the pump, and electro-responsive mechanism for controlling the last named means to effect a variation in the output of the pump, simultaneously with a variation in the speed of the electric motor.

In testimony whereof, I have signed my name to this specification in the presence of two subscribing witnesses.

AUGUST SUNDH.
